INVENTOR,
Horace Trumbull

UNITED STATES PATENT OFFICE.

HORACE TRUMBULL, OF JERSEY CITY, NEW JERSEY.

MACHINE FOR WASHING AND SEPARATING ORES AFTER BEING PULVERIZED.

Specification of Letters Patent No. 25,060, dated August 9, 1859.

To all whom it may concern:

Be it known that I, HORACE TRUMBULL, of Jersey City, in the county of Hudson and State of New Jersey, have invented an 5 Improvement in Machines for Dressing Ores; and I do hereby declare that the following is a full, clear, and exact description of the same, reference being had to the accompanying drawings, making a part of this 10 specification, in which—

Figure 1, represents a longitudinal sectional elevation taken through Fig. 2, which is a plan view of the machine.

Similar letters of reference indicate like 15 parts in both figures.

My invention relates to an improvement in washing and separating pulverized ores and matters, and for treating ores of zinc or any pulverulent ores, or mineral matters 20 where machinery is used known as a rotating baffle or a rotating table which inclines from the center to the circumference. The ores or matters are held in mechanical suspension in water and made to flow on the 25 table near the axis thereof from whence they are carried by the force of the current toward the outer edge and delivered into compartments arranged immediately under the edge of the table according to their specific 30 gravity and the component parts of the ores or matters respectively.

In this kind of machinery which has been suggested for the above named purposes great practical difficulties arise in effecting 35 the complete purification or separation of the metal from the fine particles of mineral with which it is mechanically combined. For obviating these objections revolving and fixed brushes have been tried which come in 40 contact with the pulverized ore as it passes over the table for the purpose of keeping it thoroughly agitated and thereby effect a more perfect separation. These devices though aiming at the correct principle have 45 not attained the desired object, for with either the revolving or fixed brushes the ore is impeded in its progress and water allowed to pass from it leaving it in its un-separated condition upon the table and in 50 the brushes.

My invention consists in arranging upon suitable frames, to all of which are given an oscillating motion and in pivoting these brushes to the frames so that they will press 55 upon the surface of the table or baffle with just sufficient gravity to keep the ore in

constant agitation without scraping or wiping it in heaps and retarding its passage over the table as is the case with revolving or fixed brushes; and also in giving to these 60 brushes a greater speed than that of the baffle which is to be determined by the consistency or qualities of ores to be subjected to the separating process, described as follows: 65

A, A, is the frame work for supporting the several parts about to be described. In the center of this frame is a movable upright shaft B, to which is fixed the rotary table C, which has a decline from the center 70 to the circumference of about six inches, or more or less according to circumstances. The table or what is technically termed baffle, is operated so as to have a regular rotary motion by means of a sheave E, attached to the shaft B, by which with a band the table is set in motion. Surrounding the axle B, and at a suitable distance above the center of the baffle C, is a circular gutter G the bottom of which is either 75 grated or perforated with small holes, and which is divided into two unequal apartments; the smaller one F, which takes about one quarter of the area of the trough or gutter, receives the matters to be treated 80 (which are held in suspension in water) through vertical spout H, communicating with an inclined gutter H', and delivers them on to the table C; the larger compartment F', is supplied, by means of spout I', 85 and gutter I, with a stream of water, which it delivers and distributes also over the table. The circular trough is suspended from the frame A, by vertical hangers J, J.

Surrounding the trough above described 90 and placed concentric with it is an annular ring K, supported by four posts L, and bearing upon friction rollers pivoted to said posts. This ring has an oscillating motion transmitted to it from shaft M, upon which 100 are keyed two eccentrics N, N, operating connecting rods P, P, placed opposite each other upon the ring K. From this ring proceed, radially arms R, R, R, R, inclined parallel with the surface of the table, and from 105 these arms are hung brushes S, S, two or more to each arm, which are fixed to arms T, pivoted at right angles with the said arms. The arms of the brushes are perforated so as to adjust them to or from the 110 arms as they may be deemed necessary.

The brushes may vary in size and kind, or

any number may be used and disposed at suitable distances apart upon the table, and these placed upon the arms so as to be taken off when a less number is required.

U, is a supplementary water spout through which water issues in small jets upon the table to supply the table with an additional quantity. Surrounding the table and just below its edge are channels to receive and deliver the separated matters falling from the table.

The comparative increased speed of the brushes over the table is exceedingly important to the perfect operation of the machine, for by this means the matters receive

a thorough agitation and the lighter particles in their regular succession are more rapidly carried off and the separation rendered more perfect and complete.

What I claim as my invention and desire to secure by Letters Patent, is:

The application to a rotary buckle or table such as herein above described, of vibrating brushes, when the same are arranged and operated essentially as herein above specified.

HORACE TRUMBULL.
